DUAL COMPARTMENT CONTAINER FOR LIQUIDS

Kenneth Black, P.O. Box 123, Avery, Calif. 95224

Filed Apr. 19, 1968, Ser. No. 11,530

Term of patent 14 years

U.S. Cl. D9—18
Int. Cl. D9—04

FIG. 3

FIG. 1

FIG. 4

FIG. 2

FIGURE 1 is a side elevational view of a dual compartment container for liquids showing my new design, the opposite side being substantially a mirror image thereof;

FIGURE 2 is a bottom plan view;

FIGURE 3 is a top plan view; and,

FIGURE 4 is an end elevational view looking from the right of FIGURE 1, the opposite end being substantially the same in appearance.

I claim:

The ornamental design for a dual compartment container for liquids, as shown and described.
